UNITED STATES PATENT OFFICE

108,502

DESIGN FOR A STEERING COLUMN SWITCH CASING

Wagn Trautner, Springdale, Ohio, assignor to
E. H. Kueffer, Oakland, Calif.

Application October 29, 1937, Serial No. 72,505

Term of patent 14 years

To all whom it may concern:

Be it known that I, Wagn Trautner, a citizen of the United States of America and resident of Springdale, county of Hamilton, State of Ohio, have invented a new, original, and ornamental Design for a Steering Column Switch Casing, of which the following is a specification, reference being had to the accompanying drawing forming part thereof.

Fig. 1 is a top view of the switch casing of my invention.

Fig. 2 is a side view of the switch casing of my invention.

Fig. 3 is an end view thereof.

I claim:

The ornamental design for a steering column switch casing, as shown.

WAGN TRAUTNER.
